UNITED STATES PATENT OFFICE.

JACOB CHRISTIAN HANSEN-ELLEHAMMER, OF COPENHAGEN, DENMARK.

CIGARETTE-MACHINE.

SPECIFICATION forming part of Letters Patent No. 700,040, dated May 13, 1902.

Application filed June 7, 1901. Serial No. 63,544. (No model.)

To all whom it may concern:

Be it known that I, JACOB CHRISTIAN HANSEN-ELLEHAMMER, mechanical engineer, of Istedgade 99, Copenhagen, in the Kingdom of Denmark, have invented certain Improvements in Cigarette-Machines, of which the following is a specification.

The present invention refers to improvements in cigarette-machines, and specially to the device for filling the cigarette-tubes with tobacco. The filling is effected by screwing into the properly-compressed and divided-off tobacco cylinder or rod a thin screw-shaped wire, then by means of this wire in known manner introducing the tobacco-cylinder into the paper tube, and finally unscrewing the said wire from the completed cigarette. The screwing into the tobacco-cylinder is done by turning the wire around its axis and simultaneously displace it axially at such a speed that for each revolution the wire is moved axially through a distance equal to the pitch of the screw-line. If this combined movement be adjusted in a suitable manner, the wire may be introduced even in finely-cut tobacco without in any way damaging the tobacco-cylinder.

The apparatus for filling the cigarette tubes or wrappers is by way of an example illustrated in the accompanying drawings, in which—

Figure 1 shows the apparatus seen from above. Fig. 2 shows a cross-section on the line A B of Fig. 1, and Figs. 3 to 7 are details. Fig. 8 is an enlarged detail view illustrating a different form of spiral feeder contemplated by this invention.

a is the base-plate of the machine; b and c, the two knife-shaped molds between which the tobacco in known manner is divided off and shaped into a cylinder of a suitable diameter.

d is a spout arranged in continuation of the cylindrical chamber formed between the closed molds b and c, upon which spout the cigarette tube or wrapper that has to be filled may be pushed.

In the base-plate a is arranged a slot f, parallel with the axis of the cylindrical chamber between the molds b c, in which slot a slide g may be moved forward and backward by means of the lever h, provided with a handle

i. The slide g is provided with two bearings l, in which a cylinder m, having a screw-shaped groove n, is turnably mounted. In the cylinder m is inserted a rod o, carrying the thin screw-shaped wire p, having the same pitch as the groove n. The mold c is a fixture, while the mold b is arranged to move forward and backward between the guide-rails 60 1, fixed to the base-plate. On the lower side of the mold b is fixed a pin 2, projecting through the base-plate into a slot 3, arranged in one end of a lever 5, placed underneath the base-plate a and capable of moving on a stud 4, 65 fixed to the base-plate. The lever 5 is further provided with a slot 6, in which may slide a pin 7, fixed to the main lever h, that is arranged to turn on the gudgeon 8, fixed to the base-plate. The middle portion of the slot 6 has 70 the shape of an arch of a circle, with a radius equal to the distance between the stud 7 and the gudgeon 8, and the extremities of the slot are curved on arcs eccentric to the middle portion of said slot. When moving the 75 lever h only the short distance from the position shown in Fig. 1 to the one shown in full lines in Fig. 7, the pin 7 will move in the eccentric portion of the slot 6, whereby such a movement is imparted to the lever 5 that 80 the mold b is moved from the totally open to the totally closed position. The slide g, which, by means of a pin 10, is movably connected with one end of a link k, the other end of which is movably connected with the lever h, will during 85 the aforementioned movement of the lever h only be moved so much to the left that the point of the screw-shaped wire p is standing just in front of the pressing-molds. During the further movement to the left of the lever 90 h the molds will remain closed, as the pin 7 is then moving in the portion of the slot 6 that forms an arch of a circle, with the pin 8 as a center. As already mentioned, the extremity of the slot 6 is curved into abrupt eccentric relation to the middle portion and arranged so that during the last part of the movement to the left of the lever h and when the tobacco mass has to be pushed out of the cylindrical chamber formed between the 95 molds the mold b is moved slightly apart from the mold c in order to take away the pressure from the tobacco. When the lever h is again moved to the right, the pin 7 gets into

the arch-shaped portion of the slot 6 and the molds will then assume and remain in the closed position shown in Fig. 7 until the pin gets into the last eccentric portion of the slot, 5 when the lever 5 will turn and the mold b move away from the mold c. The bearings l of the slide g are on one side provided with brackets l', having slots in which a sliding bar q may move to and fro, the sliding bar q being furnished with a pin r, projecting into the groove n. On the base-plate a are fixed two spring-arms s and t, with projections u and v. (See Fig. 3.)

The arms s and t are arranged in such a 5 manner that the prolongation w of the pin r, turning away from the cylinder m, will strike against the ends of arms s and t above the projections u and v when the slide g is moved forward and backward. The bearings l are 10 further provided with two hooks x and y, which, when the bearings through the movements of the slide g pass the arms s and t, will strike against the projections u and v and press these so far away from the slide-bar q that the pin w gets clear of the arms s or t.

The working of the apparatus is as follows: When after the paper tube e having been pushed onto the spout d the handle i is brought 5 from the position shown in Fig. 1 to the left, the slide g will also be moved to the left and the molds b c simultaneously pressed together. The slide-bar q is pushed along, together with the slide g, and the cylinder m will follow the movement without turning until the pin w bears against the end of the arm t. When this takes place, the slide-bar q will be prevented from moving any farther, and as the pin r, projecting into the groove n of the cylinder m, is now stationary, while the slide g, with the cylinder m, is moving on, this latter, besides the movement forward, will be forced to turn. This combined forward and turning movement of the cylinder m begins when 5 the point of the wire p reaches the extremity of the tobacco-cylinder between the molds b c, and the wire will consequently screw itself into the tobacco-cylinder as long as the cylinder m is turned. The moment the hook y reaches the projection v this one will be pushed away from the slide-bar q, and the pin w may now pass clear of the arm t. The turning of the cylinder m ceases, and as the wire p is now screwed completely into the tobacco-cylinder this cylinder may be inserted 10 into the cigarette tube or wrapper e by moving the slide g farther to the left until the end of the slot f has been reached. At that time the position of the hook y will be to the left of the projection u. If the slide g now be moved from the left to the right, the pin w, which at the time when this movement begins is at the right extremity of the cylinder m, will push against the arm s, and consequently the cylinder m during its further movement will turn in a direction opposite

to the one in which it was turned before, and the wire p will be screwed out of the cigarette. When the hook x reaches the projection u, the wire p will be clear of the cigarette, and the hook x disengages the pin w by pushing away the arm s. The cylinder m will no longer turn, and the slide g and slide-bar q will move together until the handle i assumes the position shown in Fig. 1. As 75 soon as the wire is screwed out of the cigarette this one is removed from the spout d and falls into a suitable receptacle.

The slide g is provided with a spring z, that drags upon the slide-bar q and prevents an 80 untimely displacement of the slide-bar.

Although I have shown and described the cigarette-filler mechanism as having a single spiral feeder, I do not limit myself to the employment of a single feeder, because I may 85 use a series of feeders, as shown by Fig. 8 of the drawings. In this figure the spiral feeders p² are shown as being formed by wires having convolutions of equal curve and disposed in crossing relation.

Having thus described my invention, I 90 claim as new and desire to secure by Letters Patent—

1. In a cigarette-machine, a filling mechanism comprising a spiral, and mechanism 95 for positively actuating said spiral to impart rotary movement and axial displacement thereto; said mechanism being effective on the advancement of the filler to the work, to give both rotary movement and axial displacement to the spiral, and then to impart axial displacement only to said spiral, while on the return movement of the filler, the mechanism screws the spiral out of the cigarette and thereafter displaces the spiral in 105 the direction only of its axis.

2. A cigarette-machine having filling means comprising a wire in the form of a spiral, means for imparting movement to the said filling means, a body m, mounted turnably 110 upon a movable slide g, to which body is fixed the screw-shaped wire p and which body is provided with a screw-shaped groove n of the same pitch as the wire, in combination with a pin r projecting into said groove and capable of being at suitable moments held firm as regards the movable slide or released therefrom in such a manner that a screwing and a straight motion is alternately imparted to the wire.

3. A cigarette-machine having a filling mechanism comprising a spiral feeder, a slide provided with spaced hooks, a slide-bar having a pin, yieldable arms disposed in the path of said pin and having projections in the 125 path of the spaced hooks, and means for actuating the slide.

4. In a cigarette-machine, a filling mechanism comprising a spiral feeder, and an actuating mechanism to impart rotary and end-wise movement to said spiral feeder, said actuating mechanism including a cam-grooved

revolute member, said spiral feeder having its convolutions corresponding in pitch to the groove of said revolute member.

5. In a cigarette-machine, a filling mechanism comprising a spiral feeder and an actuating mechanism therefor, said mechanism having a revolute and slideable member which carries the spiral feeder, means for imparting endwise movement to the carrier member, and means for rotating the carrier member simultaneously with its slideable travel; said rotating means being effective only for a part of the travel of the carrier member.

6. In a cigarette-machine, a filling mechanism comprising a spiral feeder and an actuating mechanism therefor, said mechanism including a movable base, a revolute carrier member mounted on the base and having the feeder movable therewith, means for giving reciprocating movement to the base, and means for intermittently rotating the carrier member.

7. A cigarette-machine having a filling means, comprising a device in the form of a spiral, adapted to enter and carry the filler, and means for imparting a rotary motion to the said device.

8. A cigarette-machine having a filling means, comprising a device in the form of a spiral, adapted to enter and carry the filler, and means for imparting alternately a longitudinal and a rotary motion to the said device.

9. A cigarette-machine comprising a base having an opening therein, a slide movable in the opening and carrying a device in the form of a spiral adapted to enter and carry the cigarette-filling, mechanism for imparting a revolute and endwise movement to said spiral, a mold, means thereon for holding a cigarette tube or wrapper, and means for imparting movement to the slide to pass the filling into the cigarette tube or wrapper.

10. In a cigarette-machine, a filling mechanism comprising a revolute and slideable carrier member, a filler spiral thereon, stop

devices adjacent to the path of the carrier member, and a slideable element movable with the carrier member and having means arranged to coact with the stop devices.

11. In a cigarette-machine, the combination of a cam-grooved carrier member having a spiral feeder, means to impart slideable movement to said carrier member, yieldable stops disposed in the path of projections from said carrier member, and a slideable bar mounted to travel with the carrier member for a limited distance and having means engaging with the groove of said member and other projections adapted to engage with the stop devices.

12. In a cigarette-machine, the combination of a shaping and forming mold having a movable member, a filler mechanism including a spiral feeder, mechanism to impart a traveling motion to said filler mechanism, and means for opening and closing the mold on the actuation of the filler mechanism.

13. In a cigarette-machine, the combination of a mold, a filler mechanism including a spiral feeder which is adapted to be thrust with a twisting movement into said mold, and a common mold and filler actuating mechanism having operative connection with the filler mechanism to impart slideable travel thereto and an operative connection with the mold to open and close the latter.

14. In a cigarette-machine, the combination with a forming and shaping mold, of a filler mechanism having a spiral feeder and means for giving a twisting movement to said feeder when advanced into the mold, mechanism for imparting traveling movement to the feeder mechanism and means for opening and closing the mold.

In testimony whereof I have signed my name to this specification in the presence of two subscribing witnesses.
